(57) **CLAIM**

The ornamental design for a “refrigerating apparatus,” as
shown and described.

DESCRIPTION

FIG. 1 is a perspective view of a refrigerating apparatus.

FIG. 2 is a front view of the refrigerating apparatus of FIG. 1.

FIG. 3 is a rear view of the refrigerating apparatus of FIG. 1.

FIG. 4 is a top view of the refrigerating apparatus of FIG. 1.

FIG. 5 is a bottom view of the refrigerating apparatus of FIG. 1.

FIG. 6 is a left side view of the refrigerating apparatus of FIG. 1; and,

FIG. 7 is a right side view of the refrigerating apparatus of FIG. 1.

The broken lines shown in the drawings depict portions of
the refrigerating apparatus that form no part of the claimed
design.

1 Claim, 7 Drawing Sheets
